(57) CLAIM

The ornamental design for an oral care implement, as shown and described.

DESCRIPTION

FIG. 1 is a front left perspective view of an oral care implement;

FIG. 2 is a rear right perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof; and,

FIG. 8 is an enlarged bottom view thereof.

The broken lines formed by a series of dots illustrate portions of the oral care implement that forms no part of the claimed design. The broken lines formed by alternating spaced apart long and short line segments depict the bounds of the claim and form no part of the claimed design.

1 Claim, 4 Drawing Sheets
